UNITED STATES PATENT OFFICE

2,516,405

SHIPPING CONTAINER

Willard L. Morrison, Lake Forest, Ill.

Application April 15, 1946, Serial No. 662,206

1 Claim. (Cl. 220—15)

1 My invention relates to an improvement in shipping containers and has for one purpose to provide an improved means of insulating a container having an inner and an outer chamber with insulating space between the chambers.

Another purpose is to provide a very strong means of supporting great weight in the inner container without sensibly impairing the insulation.

Another purpose is to use a low thermal conductive means to support the inner container.

Another purpose is to provide a long thermal path through the anchoring means greatly in excess of the direct distance from the inside container to the outside container.

Other purposes will appear from time to time in the course of the specifications and claim.

The invention is illustrated more or less diagrammatically in the accompanying drawings wherein Figure 1 is a perspective view of the shipping container with part of the outer container broken away and the cover separated from the container with its top surface also partly broken away;

Figure 2 is a section along the line 2—2 of Figure 3.

Figure 3 is a section on the line 3—3 of Figure 2;

Figure 4 is a detail illustrating means for varying or controlling the tension of the supporting elements;

Figure 5 is another detail illustrating said tensioning means; and

Figure 6 is a view taken on the line 6—6 of Figure 2.

Referring to the Figure 1, 1 represents the bottom floor of the outer container and 2 the supporting means so that a platform lift can be slipped under the container to transport it. The side walls 3 are shown broken away at 4 so as to give a better view of the inner container 5 and the supporting means 1. The inner container is of a size to allow adequate insulation 6 between the inner and outer containers. The amount of insulation may vary according to the use to which this device is put. It is shown only locally, but in use may fill all or most of the space between the inner and outer containers. The inner container is held in place by plywood strips which may be of any suitable size but are shown as approximately 12 inches wide and $\frac{3}{8}$ of an inch thick, running diagonally through the insulation and in alternate arrangement, some extending from the bottom edge of the inner container to the upper edge of the outer

5 container as illustrated by 7a, and others from the upper edge of the inner container to the bottom edge of the outer container as illustrated by 7b, all being embedded in the insulation 6.

In the side walls, the diagonal strips are placed in an upright position and in the bottom wall the diagonal strips are placed in a longitudinal position. These plywood strips are fastened securely at their ends to the inner and outer containers, thus giving a strong and rigid support to the inner container.

The cover 8 has insulation 6a between its upper and lower surfaces, which surfaces are held apart by suitable spacing means, such as 15 hard paper tubes 9. The lower surface of cover 8 and the upper surface 10 of the insulation of the container are covered with a thick piled carpet or suitable flexible or compressible member, 11, so that when the cover is lowered into 20 place the piles or surfaces of the two members engage together and form a snug contact, so that the cold air within cannot escape.

Referring to Figures 2 and 3, I illustrate my invention as applied to a freight car. The longitudinal beams or sills of the freight car are indicated at 12 and the freight car floor at 13. The freight car ceiling or inner roof element is indicated at 14 and the freight car sides at 15. 15 indicates an inner container which may be supported by a plurality of slats or tension members 17, corresponding to the supports 7a and 7b of Fig. 1, and similarly arranged. The sides of inner container 15 may be of corrugated metal to add stiffening strength. The space 16 between the inner container 15 and the floor, walls and roof of the car is filled by any suitable insulation, such as the insulation 6 of Fig. 1, the cross tensional supports 17 being embedded therein. It will be understood that the type of insulation employed is soft yielding and flexible or compressible.

In the form of Fig. 1 and also Figs. 2 and 3 it may be advantageous to provide means for varying or controlling the tension of the individual supports. Applying such control means to the supports 17, I illustrate stirrups or connectors 18 to which are secured bolts 19 which may pass through any suitable supporting members 20, forming part of the car of Figs. 2 and 3 or of the outer container of Fig. 1. Nuts 21 may be employed to vary or control the tension.

The use and operation of my invention are as follows:

In shipping frozen food or other perishable articles, it is possible to retain the food in its

frozen state for considerable periods by packing it in a container that is adequately insulated. To achieve this adequate insulation I use two chambers one fitting within the other and allowing a suitable distance, which may for example be approximately five inches, between the two chambers, for insulation. This distance between the chambers may vary to suit the purpose. In a freight car or motor truck body the space for insulation would be greater. Since the means of supporting the inner chamber and holding it securely forms a thermal path through the insulation between the inner and outer container, my invention employs plywood strips or other suitable material, placed diagonally in an elongated position so that the thermal path between the inner and outer container is increased considerably in length. This lessens the amount of heat that can penetrate from the outside. The plywood strips are secured tautly so as to hold the inner container in a rigid position. In some cases suitable tightening members can be introduced to tighten the various strips in order to equalize the load in all members. The plywood strips in their alternate diagonal position are used in sufficient quantity so that the inner container can carry considerable weight.

It is understood that my invention can be adapted to various uses. It can be a shipper container complete in itself as the one I illustrate. Or it can be the insulating means incorporated into a freight car, truck, airplane or any other means of transportation or storage.

In Figure 1, I have illustrated a shipping container which may be shipped as a unit, the bottom supports 2 being so formed as to permit the container to be raised by or on any suitable supporting or elevating platform. In Figs. 2 and 3, I illustrate my invention as applied to a freight car. It will be understood that it can be applied to a wide variety of transporting means.

It will further be understood that whereas I illustrate plywood supports or slats 1a and 1b

in Fig. 1 and 17 in Figs. 2 and 3, I may employ any suitable tensioning means such as rods, bars or the like, of any suitable material, preferably of materials having relatively low heat conductive characteristics.

The supports 17, in an elongated member such as the freight car of Fig. 2, may be arranged in different positions. For example, in the areas shown at A in Fig. 2, the members 17 are arranged crosswise of the roof and floor of the car. It will be understood that such variation may also be maintained in the space between the car sides 14 and the inner container 15. At the central area where the section Fig. 3 is taken, 15 all the supports 17 are shown as extending transversely of instead of longitudinally along the car.

I claim:

A shipper container comprising outer and inner housings having parallel adjacent walls, the inner housing being of smaller volumetric capacity than the outer, means for supporting the inner housing in the outer and holding it in position therein comprising a plurality of thin, flat strips located between adjacent walls, adjacent strips being oppositely inclined, each strip being anchored at one end to the wall of one container and at the other end to the wall of the other whereby lateral strips are attached to the lower wall of one container and the upper wall of the other, said strips being of such thickness that they support the load in tension much more effectively than in compression.
